US0D1003116S

(12) **United States Design Patent** (10) Patent No.: **US D1,003,116 S**
(45) Date of Patent: ** Oct. 31, 2023

(54) **INSULATING DEVICE**(71) Applicant: **YETI Coolers, LLC**, Austin, TX (US)(72) Inventors: **Kyle Edward Rogers**, Austin, TX (US); **Jeffrey Charles Munie**, Austin, TX (US); **John Loudenslager**, Austin, TX (US)(73) Assignee: **YETI Coolers, LLC**, Austin, TX (US)(**) Term: **15 Years**(21) Appl. No.: **29/855,733**(22) Filed: **Oct. 6, 2022**

CLAIM

The ornamental design for an insulating device, as shown and described.

DESCRIPTION

FIG. 1 is a top, front, right perspective view of an insulating device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines represent stitching that forms no part of the claimed design. The uneven-length broken lines immediately adjacent to the shaded area define the bounds of the claimed design and form no part thereof. The broken lines within the disclaimed area represents a zipper that forms no part of the claimed design.

FIG. 1

FIG. 2**FIG. 3**

FIG. 4**FIG. 5**

FIG. 6

FIG. 7
